UNITED STATES PATENT OFFICE.

SIGVALD T. JENSSSEN, OF PHILADELPHIA, PENNSYLVANIA.

CARD-HOLDER.

1,274,887.

Specification of Letters Patent.

Patented Aug. 6, 1918.

Application filed April 27, 1917. Serial No. 164,854.

To all whom it may concern:

Be it known that I, SIGVALD T. JENSSSEN, a citizen of the United States, residing at Philadelphia, in the county of Philadelphia and State of Pennsylvania, have invented 5 certain new and useful Improvements in Card-Holders, of which the following is a specification.

My invention relates to improvements in 10 card holders, the object of the invention being to provide a simple, inexpensive device, which can be attached to a window or door frame, and which will most efficiently hold a card, photograph, or other similar article 15 against the glass of the window or door so that the article can be readily seen from the opposite side of the window or door.

A further object is to provide a card 20 holder which is especially adapted for use in connection with office doors, enabling the office holder to readily position the card against the inner face of the glass door so as to indicate when he will return, and so construct the card holder that it will most 25 efficiently hold the card in a flat position against the glass, regardless of the thickness of the door frame.

With these and other objects in view the invention consists in certain novel features 30 of construction and combinations and arrangements of parts as will be more fully hereinafter described and pointed out in the claims.

In the accompanying drawings:

35 Figure 1 is a fragmentary view in elevation, of a door illustrating my improved card holder, in full lines in operative position and in dotted lines in inoperative position.

40 Fig. 2 is a view in side elevation of the card holder removed.

Fig. 3 is a view in section on the line 3—3 of Fig. 2, and

45 Fig. 4 is a view in section on the line 4—4 of Fig. 2.

1 represents the door which is ordinarily 50 of wood, and 2 is the glass or transparent portion of the door which, in office buildings, is usually frosted or otherwise treated 55 to permit it to admit light without allowing a view of the room.

A card such as indicated at 3, in order to 60 be seen from the outside of the door must be pressed tightly and smoothly against the 65 inner face of the glass, and my improved

card holder 4 efficiently performs this function.

The card holder 4 consists of a strip of 70 spring metal 5 given a general compound curvature adjacent one end as shown at 6, 60 and at one end preferably rounded as shown at 7. This rounded portion 7 is provided centrally with an opening 8 to receive a screw, nail, or other securing device 9 which is driven into the door 1. The rounded portion 7 is provided on its inner face with a circular bearing ridge 10 which may be formed by pressing the metal, as clearly 75 shown in Fig. 4.

This bearing ridge 10 permits the card 80 holder to be easily turned from the position shown in full lines to that shown in dotted lines in Fig. 1, and spaces the main portion of the device away from the door so as not to disfigure the same.

The spring metal strip 5 preferably tapers 85 or reduces in width from its rounded end 7 to its free end 12 where it is provided with an opening 13 to receive a rivet 14. The rivet 14 is counter-sunk at one end in a disk 90 11 and extends through a spacing sleeve 15, through the opening 13, and through a washer 16, and upset at its end as clearly shown in Fig. 3.

The spacing sleeve 15 at its end adjacent 95 the spring metal strip 5, is beveled or made conical and the connection between the sleeve and the strip is a loose one, so that the disk 11 is permitted movement in all directions, as well as a rotary movement to enable the disk to assume the necessary angular position relative to the spring metal strip 5, and always lie flat against the card 3 to press the same firmly and smoothly 100 against the inner face of the glass 2.

When the card is not desired, the holder may be swung to the position shown in dotted lines in Fig. 1, and will, by the elasticity of strip 5, maintain itself in any position to which it is moved.

When it is desired to hold the card, it is simply necessary to hold the card against the glass and then swing the card holder to the position shown in full lines, and the disk 11 will bear smoothly and flatly against the card regardless of the angular or curved disposition of the spring strip 5.

While I have illustrated my improved card holder in connection with a door, it is of course to be understood that it may be 110

used for various other purposes, such as holding photographs or advertising matter against store windows or showcases, and I therefore do not limit myself to any particular use or to the precise details set forth, but consider myself at liberty to make such changes and alterations as fairly fall within the spirit and scope of the appended claims.

Having fully described my invention what I claim as new and desire to secure by Letters Patent is:

1. A device of the character described, comprising a spring strip adapted to be connected to a support, and a disk loosely connected to the free end of the strip to move in different planes.

2. A device of the character described, comprising a spring strip adapted to be secured at one end to a support, and a disk spaced from the other end of the strip, having a rotary connection with the strip, and having also a limited angular movement relative to the strip.

3. A device of the character stated, comprising a spring member of considerable length compared with its width and having one terminal provided with an opening to

receive a securing device, a disk for the second terminal thereof and limited rotary and universal-joint connection between the disk and the second terminal, one of the members of the joint spacing the disk from the terminal, whereby rotary movement and limited universal movement of the disk are permitted.

4. A device of the character described, comprising a strip of spring metal curved between its ends, said strip, at one end, having an opening for the reception of a securing device, and having a circular ridge on its inner face concentric with said opening, a disk, a rivet loosely connecting the disk with the free end of the strip, and a spacing sleeve on the rivet between the disk and the strip, said spacing sleeve having a tapering end adjacent the strip.

In testimony whereof I have signed my name to this specification in the presence of two subscribing witnesses.

SIGVALD T. JENSSSEN.
